WIRE SPLICER

Julian Rogoff, New York, N. Y., assignor to
 Burndy Engineering Co. Inc., a corporation of
 New York

Application March 25, 1939, Serial No. 264,053

8 Claims. (Cl. 24—126)

This invention relates to improvements in connectors and more particularly to connectors for splicing wires.

Such wire splicers generally consist of a tubular envelope or shell body with each end tapered, a set of wedge shaped jaws in each end and a coiled spring between the sets of jaws to keep them in contact with the tapered portions of the envelope. When a wire is inserted into the connector, and tension is then exerted on the wire, the jaws are forced into contact with the wire and the inner surface of the tapered envelope by the spring. The surface of the jaws that come in contact with the wire are serrated or roughened to increase friction or "bite" between jaws and wire, whereas the back of the jaws are smooth and ride on the smooth inner surface of the envelope. The result is that the "bite" or friction between wire and jaws is greater than the friction between jaws and envelope so that the jaws will pull forward with the wire into the tapered envelope. As the jaws move forward, the taper forces them to exert increased pressure on the wire and grip the wire even more securely. Thus, the greater the tension on the wire, the more secure is the grip on the wire.

An object of my invention therefore, is to provide a frictional value between the jaws and the conductor, which will at all times be greater than the friction between the jaws and the envelope.

The coiled spring depended on to force the jaws into the tapered portion of the envelope provides the initial pressure on the wire, preventing its removal. A spring, I have found, is an inefficient mechanism for this purpose. The pressure of the spring on the jaws is greatest when the jaws are in receded position and least, when the jaws are in advanced position. However, it is important when the jaws are in advanced position and when tension is first applied to the wire, that the pressure forcing the jaws into the tapered portion of the envelope be at a maximum. Unfortunately, when the jaws are in advanced position, the spring is fully extended and the least, not the most, pressure is exerted on the jaws.

An additional object, consequently, consists in providing the connector with sustained pressure applying means for propelling the jaws into the tapered end of the envelope. A corollary object is to eliminate dependence on coiled springs for this purpose.

Wire splicers, as previously made, would work efficiently as long as some factor did not upset

the delicate balance of friction between the jaws and wire, as compared with the friction between the jaws and envelope. Unfortunately, this balance is relatively easy to upset and very often wires would pull free of the connector instead of being properly gripped. For example, if the splicer was dropped in dirt or sand, foreign matter would get into the connector, often between the jaws and envelope and by increasing the friction at that point, would prevent the jaws from pulling forward into the taper. Sometimes, in swaging the tapered ends of the envelope, rough ridges might be raised on the inner surface which would effectively increase the friction between jaws and envelope. In addition, the jaws themselves may be forged or machined with a rough surface which may be a cause of increased friction between jaws and envelope. All these causes and others, can and do cause wire splicers to fail to properly grip wires inserted into them.

Hence, another object of this invention is to provide an auxiliary grip of sufficient strength so that the presence of dirt or other foreign matter in the connector will not prevent the jaws from pulling forward into the tapered portion of the envelope.

Wire splicers, of the general type herein described, are practically always used on overhead lines, exposed to wind, sleet, storms, etc. Very often these lines are subject to considerable vibration and swaying. Under such conditions momentary release and resumption of the tension on the wires connected by the splicers is quite possible. Where the tension is momentarily released, the grip on the conductor is maintained only by the spring pressure on the jaws, which, as shown above, is least when it should be greatest.

Thus, a further object of this invention is to provide a wire splicer wherein the wire is gripped positively at low tension.

The alternate release and resumption of tension in this type of connector is sometimes accompanied by a rotational movement of the wires with respect to the jaws. These actions have a wearing effect on the teeth of the jaws, and on the conductor, which is ultimately destructive of the gripping action. I have found that if the conductor is moved in the connector, the jaws should move with it.

Another object, therefore, consists in providing means for preventing relative motion between jaws and conductor.

Further objects consist in providing a grip for

the conductor independent of the main gripping jaws; in providing a positive gripping means on the conductor which will force the main gripping jaws to go into action the instant tension is applied; in providing auxiliary gripping means for supplementing the gripping action by the main gripping jaws; and in obtaining all the foregoing objects in a simple and commercially expedient device, easy and inexpensive to manufacture and 10 without adding additional parts to the existing types.

I accomplish these and other objects and obtain my new results as will be apparent from the device described in the following description, particularly pointed out in the attached claims, and 15 illustrated in the accompanying drawing, in which:

Fig. 1 is a side view of one end of a splicer showing one form of the invention, the envelope 20 being in section.

Fig. 2 is a cross-sectional view of the same taken along the line 2—2 of Fig. 1, and in the direction indicated by the arrows.

Fig. 3 is a similar view taken along line 3—3 25 of Fig. 1.

Fig. 4 is a sectional view of one end of my splicer taken along line 4—4 of Fig. 3.

Fig. 5 is a side view of another modification with one end in section and the other end with 30 just the envelope in section.

Fig. 6 is a cross-sectional view taken along the line 6—6 of Fig. 5.

Fig. 7 is a sectional view of one end of still another modification.

35 Figs. 8 and 9 are marks of some gripping means employed in the invention.

Referring more particularly to the drawing, reference numeral 10 of Figs. 1, 2 and 3, indicates the tubular envelope, with each end tapered as 40 at 11, 12, 13 and 14, the gripping jaws, respectively, located in each tapered end; 15, the coiled spring, holding the sets of jaws apart; 16, a cap for enclosing the end of the spring; 17, the "spider" for holding the jaws in spaced relationship to each other; and 18, the conductor, inserted in the open end 19 of the splicer.

The invention, in these figures, is shown incorporated in the "spider", or cap 17, which consists of a body or end section 20, having extending 50 fingers 21, 22 and 23, each apertured as at 24, 25 and 26, in the form shown, to receive the rivet head 27, 28 and 29, shown as integral with the jaws. Exceptional flexibility of the "spider" is obtained by cut-outs 30, 31 and 32, forming a Y 55 as seen from the view shown in Fig. 3, which cut-outs terminate in tongues 33, 34 and 35, in extending fingers 21, 22 and 23, respectively.

Thus each extending finger is made more flexible by forming the tongue therein, leaving side 60 walls 36 and 37, in the case of finger 22, up to the end seated on the jaw 13 where the aperture 25 is formed.

This flexibility is desirable where surface irregularities in the inside of the shell cause the jaws 65 to assume slightly changed longitudinal positions, or where it is desired to grip various sized conductors.

Each pair of adjacent fingers are supported by the sections 38, 39 and 40 of metal remaining 70 in the end section 20, after the cut-outs are made. Thus, finger 22, supporting jaw 13, is supported by end sections 38 and 39; finger 23, by end sections 39 and 40; and finger 21, by end sections 40 and 38.

75 The tongues 33, 34 and 35 are inwardly bent,

as shown in Fig. 1, and have a length sufficient to positively engage a conductor or wire inserted therein. The biting edges of the tongues may be V-shaped, as shown by the mark 40x, formed on conductor 41, or arch-shaped, as shown by 5 mark 42, on conductor 43, or some other suitable shape, designed to prevent rotation of the conductor with respect to the jaws to which they are attached. Eliminating such relative movement, as has been previously stated, will 10 prevent wear of the surface of the conductors, and gripping surfaces of the jaws.

The modification just described combines the ordinary jaw spider and the positive initial-grip- 15 means.

A somewhat similar combination is shown in Figures 5 and 6. Here the jaws 50, 51 and 52 are provided with apertures 53, 54 and 55. The spider or metal cap 56 is formed with extending fingers or prongs 57, 58 and 59, passing through 20 apertures 53, 54 and 55, respectively, and engaging wire end 60 extending therethrough, similarly to tongues 33, 34 and 35 as in Fig. 1.

Thus the extending fingers or tongues for positive 25 initial grip, pass through the jaws themselves and support them in proper alignment.

In the remaining modification shown in Fig. 7, the jaws 61 are provided with inwardly projecting shoulders 62, passing through apertures 63 positioned between annular ridge 64, and cylindrical gripping section 65 integral thereto. A set screw 66, passes through transversely formed, threaded recess 67, in section 65, to positively grip conductor 68 passing through the recess 69 located longitudinally of both ridge 64 and section 65. A slot 70, in envelope 71, permits a tool to be inserted for manipulating set screw 66.

A washer 72 is positioned between each set of jaws to prevent the conductor or wire 68 from projecting too far beyond its gripping section 65. 40

In each of the foregoing modifications, it will be apparent that the conductors are gripped even at "zero" tension in the wires themselves. Furthermore, when tension is created, the jaws are positively forced into the tapered ends of the 45 envelopes or shells, simultaneously increasing the gripping pressure on the conductor. When the tension is released or if the conductor is twisted, the jaws are nevertheless positively positioned with respect to the conductor and will move 50 therewith.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

What I claim and desire to secure by Letters Patent, is as follows:

I claim:

1. A connector comprising a shell body having 70 a cone-shaped internal surface and an opening therein adjacent the smallest cross-section of the cone-shaped surface for the insertion of a conductor; a plurality of wedge-shaped gripping jaws each with conductor and shell engaging sur- 75

faces and an end aperture; and a sheet metal spider having projecting fingers extending therefrom passing through and operatively engaged with the end apertures in each jaw and forming 5 conductor gripping means.

2. A connector comprising a shell body having a cone-shaped internal surface and an opening therein adjacent the smallest cross-section of the cone-shaped surface for the insertion of a conductor; a plurality of wedge-shaped gripping jaws each with conductor and shell engaging surfaces; and a sheet metal cap having projecting fingers in operative engagement with said jaws, and provided with a cut-out extending into each finger 10 for producing additional flexibility therein, the metal from said cut-out extending radially to form conductor gripping means.

3. A connector comprising a shell body having a cone-shaped internal surface, and an opening 20 therein, adjacent the smallest cross-section of the cone-shaped surface, for the insertion of a conductor; a wedge-shaped gripping jaw with conductor and shell engaging surfaces; and means for operative engagement with the wedge-shaped gripping jaw, positioned within the shell body for engaging the conductor inserted into the connector and applying pressure thereto, independently of any longitudinal tension in the conductor.

30 4. A connector comprising a shell body having a cone-shaped internal surface, and an opening therein, adjacent the smallest cross-section of the cone-shaped surface, for the insertion of a conductor; a wedge-shaped gripping jaw with conductor and shell engaging surfaces; and means, for operative engagement with the wedge-shaped gripping jaw, positioned within the shell body for engaging the conductor inserted into the connector and applying pressure thereto, independently of any longitudinal tension in the conductor, said means connected to said wedge-shaped gripping jaw whereby a movement by the conductor engaged by said means will cause said means and jaw to move with the conductor.

45 5. A connector comprising a shell body having a cone-shaped internal surface, and an opening therein, adjacent the smallest cross-section of the cone-shaped surface, for the insertion of a conductor; a wedge-shaped gripping jaw with conductor and shell engaging surfaces; and means, for operative engagement with the wedge-

shaped gripping jaw, positioned within the shell body for engaging the conductor inserted into the connector and applying pressure thereto, independently of any longitudinal tension in the conductor, said wedge-shaped gripping jaw positioned 5 between the opening in the shell body, and said means.

6. A connector comprising a shell body having a cone-shaped internal surface and an opening therein adjacent the smallest cross-section of the cone-shaped surface for the insertion of a conductor; a plurality of wedge-shaped gripping jaws each with conductor and shell engaging surfaces; means for operative engagement with the wedge-shaped gripping jaws positioned 10 in the shell, for supporting said jaws in radial alignment about the conductor, said means provided with conductor engaging surfaces, independent of said jaws.

7. A connector comprising a shell body having a cone-shaped internal surface, and an opening 20 therein, adjacent the smallest cross-section of the cone-shaped surface, for the insertion of a conductor; a wedge-shaped gripping jaw with conductor and shell engaging surfaces; and 25 means, for operative engagement with the wedge-shaped gripping jaw, positioned within the shell body having a longitudinal recess therein for the insertion of the conductor therethrough, a transversely extending tapped aperture, extending 30 to the longitudinal recess, and a set-screw for threaded engagement therethrough for securing the end of the conductor inserted into the recess, to said means.

8. A connector comprising a shell body having a cone-shaped internal surface, and an opening therein, adjacent the smallest cross-section of the cone-shaped surface, for the insertion of a conductor; a wedge-shaped gripping jaw with conductor and shell engaging surfaces; and 40 means, for operative engagement with the wedge-shaped gripping jaw, positioned within the shell body for engaging the conductor inserted into the connector and applying pressure thereto, independently of any longitudinal tension in the 45 conductor, said means having gripping edges, adapted to resist longitudinal and rotational movement of the conductor.

JULIAN ROGOFF. 50
